Primary Examiner — Deanna L Pratt

(57) **CLAIM**

I claim the ornamental design for a commercial/office seating, as shown.

DESCRIPTION

FIG. 1 is a front elevation view of a commercial/office seating in accordance with my new design;

FIG. 2 is a rear elevation view thereof;

FIG. 3 is a top elevation view thereof;

FIG. 4 is a bottom elevation view thereof;

FIG. 5 is a side elevation view thereof;

FIG. 6 is a side elevation view thereof, for the side opposite that of FIG. 5;

FIG. 7 is a front perspective view thereof;

FIG. 8 is a rear perspective view thereof;

FIG. 9 is a front elevation view of another embodiment of a commercial/office seating in accordance with my new design;

FIG. 10 is a rear elevation view thereof;

FIG. 11 is a top elevation view thereof;

FIG. 12 is a bottom elevation view thereof;

FIG. 13 is a side elevation view thereof;

FIG. 14 is a side elevation view thereof, for the side opposite that of FIG. 13;

FIG. 15 is a front perspective view thereof; and,

FIG. 16 is a rear perspective view thereof.
